UNITED STATES PATENT OFFICE.

GEORGE S. HAMMOND, OF CHICAGO, ILLINOIS.

CIGARETTE-FORMER.

SPECIFICATION forming part of Letters Patent No. 706,981, dated August 12, 1902.

Application filed October 15, 1901. Serial No. 78,687. (No model.)

To all whom it may concern:

Be it known that I, GEORGE S. HAMMOND, a citizen of the United States, residing in Chicago, in the county of Cook and State of Illinois, have invented a certain new and useful Improvement in Cigarette-Formers, of which the following is a specification.

The invention relates to that class of cigarette formers or devices adapted to be placed in the pocket of the user or otherwise carried about the person, and has for its objects to construct a former or device of small size and of great simplicity without any loose parts and which will enable either thick or thin cigarettes to be rolled or formed, as may be desired, and have the cigarette either tight or loose rolled to suit the taste of the smoker; to adjust the length of the former or device readily and quickly to suit different lengths of paper, thus enabling papers of varying lengths to be successfully used in the same former or device; to insure the closing of the ends of the tube of paper as the cigarette is formed, thus preventing the free escape of fine or granulated tobacco in the act of forming the cigarette, and to improve generally the construction of the former or device as to the component parts thereof; and the invention consists in the features of construction and combinations of parts hereinafter described and claimed.

In the drawings illustrating the invention, Figure 1 is a top or plan view showing the preferred form of construction of the former or device, with the flap partially opened for the reception of the cigarette-paper and the tobacco; Fig. 2, a top or plan view with the flap closed; Fig. 3, a top or plan view with the flap open and in position to carry thereon the made cigarette for its removal from the device or former; Fig. 4, a cross-section with the flap as in Fig. 1, showing the paper in place and the tobacco thereon; Fig. 5, a cross-section with the parts as in Fig. 2, showing the cigarette in its shaped condition; Fig. 6, a cross-section with the parts as in Fig. 3, showing the cigarette lying in the flap in position for removal from the former or device; Fig. 7, a top or plan view of a modified construction for the former or device, the flap being omitted; Fig. 8, a side elevation of the former or device of Fig. 7; Fig. 9, a top or

plan view showing another modification in the construction of the former or device, one of the plugs or stops being adjustably fixed, 55 while the other plug or stop is hinged, so as to be swung clear of the end of the forming-trough; Fig. 10, a similar view to Fig. 9, showing the hinged plug or stop swung out of line to clear the end of the forming-trough; 60 Fig. 11, a detail showing the adjustable plug or stop d' , carried by a hinged or swinging socket; Fig. 12, a cross-section through the former or device showing the free edge of the flap beveled, and Fig. 13 a cross-section 65 through the former or device showing the free edge of the flap beveled on its exterior face and provided with a raised ridge or notch on its inner face; and Fig. 14, a cross-sectional view of the trough and flap, showing the same fluted or corrugated. 70

The preferred form of construction for the former or device is illustrated in Figs. 1 to 6, both inclusive. The former or device of the preferred construction has a main body or trough a , of the required length and depth to receive the cigarette-papers, for placing thereinto the tobacco from which the cigarettes are to be made. This main body or trough a may be made of sheet metal of any suitable 80 character or of any material of a nature to be formed into a trough shape for receiving the paper and the tobacco. A flap b , also of sheet metal and of semicylindrical shape in cross-section, is hinged at one edge to one edge of the 85 body or trough a by a suitable hinge or connection c , which will permit the flap to be swung over and away from the open side of the body or trough. The free edge of the flap b , if the metal or material of which it is 90 formed is sufficiently thin, can be left intact, or the edge can be beveled on one side, so as to leave a sharp edge b' , as shown in Fig. 12, which gives an increased bite on the paper in drawing the paper tight around the 95 tobacco in making the cigarette, and, if desired, the inner face of the flap at the free edge can be formed so as to have a ridge or recess b^2 , which serves as a grip for the inner fold of the cigarette-paper to prevent the cigarette from shifting its position or unrolling as the paper is drawn tight. 100

One end of the body or trough has an adjustable plug or stop d , which is held in a

clasp or socket *e*, formed with or attached to the end of the body or trough, which clasp or socket in the construction shown in Figs. 1, 2, and 3 has a slot *e'* and is of a less diameter than the diameter of the plug or stop, so as to furnish a spring action by which the plug or stop will be held in an adjusted position, and the clasp or socket is surrounded in the construction shown in Figs. 1, 2, and 10 3 by a sliding retaining-band *f* to slip over the end of the flap and hold the flap closed when the former is out of use. The opposite end of the body or trough *a* has a plug or stop *g*, which may be either adjustable or 15 fixed, and this plug or stop is carried by a clasp or socket *h*, which, as shown, is continuous, but which might be a slotted clasp or socket similar to *e*, in which case both plugs or stops would be adjustable instead of 20 only one, though for general use one adjustable plug or stop is deemed sufficient. The inner end of each plug or stop extends into the body or trough and forms a rest or support for the ends of the flap in the construction 25 shown in Figs. 1, 2, and 3, so that when the flap is closed, as shown in Fig. 2, a firm support therefor will be formed by the plugs or stops. The plug or stop *d* when only one adjustable plug or stop is used can be advanced and receded for its inner end to be 30 the required distance from the inner end of the plug or stop *g* to leave a length of space for the length of paper, and when adjusted the plug or stop will be held in place against 35 ordinary usage by the friction of the slotted clasp or clamp, which friction, however, is not strong enough to prevent the advancing and receding of the plug or stop with the exertion of a little force on the part of the user 40 of the former or device.

In use the adjustable plug or stop is moved in or out, as required, for the length of cigarette-paper to lie between the inner ends of the two plugs or stops, with but little, if any, 45 space between the plugs or stops and the edges of the paper, so that when the paper is rolled into shape its edges will abut or nearly abut the end faces of the plugs or stops, thus preventing escape of tobacco at the ends of 50 the paper. The flap *b* is opened in use, and a leaf or sheet of cigarette-paper is laid in the main body or trough *a* of the former or device and is held therein by the tip of the first finger of the hand, which holds the former 55 or device, or in any other suitable manner, it being understood that the former or device is held by one hand in practically a horizontal position, and ordinarily the left hand performs this work with the thumb resting against the 60 end of the flap and the fingers against the back or outer face of the body or trough. The adjustable end plug or stop is then moved so as to leave the space between the ends of the plugs or stops the same as or a trifle 65 longer than the length of paper, as above described. The tobacco is then placed in the paper and is spread evenly in the space be-

tween the plugs or stops on the paper in the main body or trough with the fingers of the unemployed hand or otherwise, and after the 70 tobacco is partly spread the finger-tip of the employed hand holding the paper in place can be withdrawn, as the tobacco will retain the paper in the main body or trough of the former or device. The side edge of the paper which overlies the flap is turned down upon the tobacco and is there held while the opposite edge of the paper is turned there-over, and this overlapping edge of the paper is drawn tightly over the edge of the flap in 80 order to draw and tighten the paper around the tobacco with a sufficient tension to draw the cigarette as a whole closely against the inner face of the flap, which causes the edge of the flap to grip the inner fold of the paper, preventing the cigarette as a whole from shifting its position or unrolling. The cigarette as thus formed is to be held without relaxing the overlapping edge of the paper firmly against the inner face of the flap by 85 the tension of the paper, preferably using the left hand for the purpose, which permits the left thumb to be placed upon the cigarette at the open space between the main body or trough and the flap of the former or device, 90 and in this condition the main body or trough is turned away from the flap, using the unemployed hand, which turns the cigarette out from the main body or trough upon the flap, the thumb of the retaining-hand holding the 100 cigarette upon the flap, while the fingers of that hand hold the loose edge of the paper against the under side of the flap. The cigarette is now completely formed and is removed from the flap by sliding it along the flap 105 lengthwise until the end of the flap is clear of the end of the cigarette, and when the cigarette is removed the loose edge of the paper can be moistened and sealed in the usual way, or, if desired, the cigarette may be moistened 110 for sealing before it is turned out from the trough.

The device is very simple in construction and will perform the required work of making cigarettes in a positive and reliable manner, 115 enabling cigarettes to be either tight or loose rolled, as may be desired, and permitting large or small sized cigarettes to be made with the same former or device. The adjustable end plug or stop insures the adaptation of 120 the former or device to cigarette-papers of varying lengths by simply advancing or receding the adjustable plug or stop, or if both plugs or stops are adjustable then adjusting either or both of them, as may be desired. 125 The flap can be turned so as to leave a clear space for the insertion of the paper and dropping the tobacco thereinto, as shown in Fig. 4, and when the paper and tobacco are in place the flap can be closed so as to have the 130 paper receive the tobacco, as shown in Fig. 5, and when the cigarette is shaped the main body or trough can be turned away from the flap for the formed cigarette to lie in the flap

in position for removal, as shown in Fig. 6, and these various operations can be readily and quickly performed. The former or device is light and can be carried in the pocket or 5 about the person of the user without any trouble or inconvenience when not in use, and in use the former or device can be held in one hand for the insertion of the paper and the filling of the tobacco thereinto with the other 10 hand, and the manipulation of the former or device is under a perfect control by the hands of the operator, so that the cigarette can be formed into shape and removed very quickly and without any liability of the escape of fine 15 or granulated tobacco, when used for cigarettes, at the ends of the paper, as the plugs or stops will hold the ends of the paper closed until the tobacco is sufficiently compacted within the paper, so as to be held therein when 20 the cigarette is removed from the former or device.

It is possible and practical to employ successfully a construction of main body or trough having at one or both of its ends an 25 adjustable plug or stop, and a construction of this nature is shown in Figs. 7 and 8, in which the main body or trough *a* is of the same general formation and construction as the body or trough already described for the 30 construction of Figs. 1, 2, and 3, having at each end, however, in the construction of Figs. 7 and 8 a continuous clasp or socket, one of which, *e*³, has a diagonal thread or indentation *e*², which furnishes a means for advancing and receding the adjustable plug or stop *d*, the turning of the plug or stop causing the diagonal thread or indentation to operate as a screw on the plug or stop, and the other end has a plug or stop *g* and a clasp or 35 socket *h*, corresponding to the same parts in the construction of Figs. 1, 2, and 3. Moreover, a screw-threaded plug *d'* may be employed, as shown in Figs. 9 and 10, the threads of which enter the thread *e*² of the clasps *e*³. 40

45 The use of the former or device of the construction shown in Figs. 7 and 8 is substantially the same as already described, so far as entering the sheet of paper and adjusting the end plug or stop and depositing and manipulating the tobacco in the paper are concerned. The omission of the flap necessitates the folding down of one edge of the paper upon the tobacco, and while the edge is held in place, preferably by the thumb, have the fingers 50 fold the other edge of the paper upon the first edge and then drawing the outer fold or overlapping edge of the paper down over the edge of the body or trough, which tightens the paper around the tobacco, the cigarette being 55 prevented from unrolling by reason of its being drawn closely against the edge of the trough, as the edge of the trough will grip the inner fold of the paper when the tension draws the tobacco toward it. After the paper 60 has been drawn sufficiently tight around the tobacco the overlapping edge is held firmly against the outer face of the body or

trough by the fingers of one hand with the thumb of that hand upon the cigarette, and in this condition the body or trough is gently 70 turned and drawn away with the unemployed hand, which movement causes the cigarette to slide from the body or trough and remain in the hand between the fingers and thumb by which it is held, when the loose outer edge 75 which lies across the finger-tips can be moistened and sealed as usual; but, if desired, the edge of the paper may be moistened for sealing before the cigarette is removed from the main body or trough. 80

The essential features of construction which enter into the former or device of this invention are the main body or trough for forming the cigarettes in connection with end plugs or stops, one or both of which are adjustable, 85 and various arrangements for removing the cigarette after formation from the body or trough can be employed. Instead of turning the cigarette into a coöperating flap or turning the body or trough away from the cigarette, as already described, an end plug or stop, preferably the unadjustable one, can be carried by a clasp or socket *h'*, attached to the end of the body or trough by a hinge *i*, as shown in Figs. 9 and 10, so that when the 95 cigarette is formed in the manner described for the construction of Figs. 7 and 8 the hinged end plug or stop can be turned out of line with the end of the body or trough, as shown in Fig. 10, which permits the cigarette 100 to be slipped lengthwise out of the body or trough or the trough to be withdrawn with the cigarette held in the hand with its overlapping edge free to be moistened and sealed in the usual manner. It is evident that the 105 adjustable plug or stop could be carried by a hinged clasp or socket, as shown in Fig. 11, in which the clasp or socket of Fig. 7, with its advancing thread or indentation, is attached by a hinge *j* to the end of the body or trough, so 110 that it can be swung out of line of the end of the trough for removal of the cigarette, and it is also evident that both end plugs or stops could be carried by hinged sockets or clasps, if so desired, so that either end plug or stop could 115 be swung away from the end of the trough, or by connecting the hinged sockets or clasps both end plugs or stops could be simultaneously swung away from the ends of the body or trough. The adjustment of the plug or 120 stop can be attained in any suitable manner, so long as the construction enables the plug or stop to be readily advanced and receded and when in an adjusted position held therein permanently until the paper, to the length of 125 which the space between the plugs or stops is adjusted, has been used up, so that it is only necessary to set the plugs or stops for one sheet of paper in a package, as the remaining sheets will be of the same length. The former 130 or device, irrespective of its details of construction, so long as it has a body or trough and an adjustable end or ends, possesses the advantages and utility set forth for the con-

struction of Figs. 1, 2, and 3; but the construction of said figures is the one preferred for general use. The flap formation when the flap is closed makes, in connection with the main body or trough, a perfect mold in which to shape the cigarette, as shown in Fig. 5, and it is preferred to have the flap of a length to overlie the ends of the plugs or stops; but a flap foreshortened at each end is practical for use, and with a foreshortened flap the former or device is specially applicable in shaping very slim cigarettes. The ridge or notch on the inner face of the flap extends the full length of the flap and serves the purpose of effectively gripping the inner fold of the paper, preventing the cigarette from shifting its position or unrolling as the paper is drawn tight, and it is obvious that for this purpose the ridge or notch may be duplicated, giving the inner face of the flap a serrated construction, if so desired, and the main body or trough and the flap might be made of corrugated material instead of plain material, as shown.

25 What I claim as new, and desire to secure by Letters Patent, is—

1. In a cigarette-former, the combination of a body or trough, a flap hinged to one edge of the body or trough, and end plugs or stops, one of which is adjustable for spacing the distance to suit the requirements of and furnish abutments for the ends of different lengths of paper, substantially as described.

2. In a cigarette-former, the combination of a body or trough for receiving the paper and tobacco, and a plug or stop at each end of the body or trough, for forming an abutment for each end of the paper against escape of tobacco in shaping the cigarette, one of the plugs being adjustable to vary the length of space in the body or trough, substantially as described.

3. In a cigarette-former, the combination of a body or trough for receiving the paper and tobacco, a clasp or socket at each end of the body or trough, and a plug or stop carried by each clasp or socket and forming an abut-

ment for each end of the paper and the tobacco in shaping the cigarette, one of the plugs being adjustable to vary the length of space in the body of the trough, substantially as described.

4. In a cigarette-former, the combination of a body or trough for receiving the paper and tobacco, a clasp or socket at each end of the body or trough one of which is hinged to the body or trough, and a plug or stop carried by each clasp or socket and forming an abutment for each end of the paper in shaping the cigarette and permitting the withdrawal of the cigarette by swinging the hinged clasp or socket out of line of the end of the body or trough, substantially as described.

5. In a cigarette-former, the combination of a body or trough, a flap hinged to one edge of the body or trough, a clasp or socket at each end of the body or trough, and a plug or stop carried by each clasp or socket and forming an abutment for each end of the paper in shaping the cigarette and for the inner face of the end of the flap, substantially as described.

6. In a cigarette-former, the combination of a body or trough, a flap hinged to one edge of the body or trough, a clasp or socket at each end of the body or trough, a plug or stop carried by each clasp or socket, one plug or stop adjustable in its clasp or socket for spacing the distance between the plugs or stops to furnish abutments for the ends of papers of varying lengths, substantially as described.

7. In a cigarette-former, the combination of a body or trough receiving the paper and tobacco, a flap hinged at one edge of the body or trough, a clasp or socket at each end of the body or trough, and a plug or stop adjustably carried by each clasp or socket for spacing the distance between the plugs or stops to furnish abutments for the ends of papers of different lengths, substantially as described.
